UNITED STATES PATENT OFFICE.

JOHN W. LIMBERT, OF MUNCIE, INDIANA.

FASTENER FOR JAR-CLOSURES.

1,322,125.

Specification of Letters Patent. Patented Nov. 18, 1919.

Application filed January 4, 1919. Serial No. 269,617.

To all whom it may concern:

Be it known that I, JOHN W. LIMBERT, a citizen of the United States, residing at Muncie, in the county of Delaware and State 5 of Indiana, have invented certain new and useful Improvements in Fasteners for Jar-Closures, of which the following is a specification.

This invention relates to jar closures and 10 more particularly to a novel form of fastener therefor.

The object of the invention is to provide a fastener of simple and inexpensive construction capable of being readily applied to an 15 ordinary jar and by means of which the lid or closure thereof may be securely clamped in position over the mouth of the jar so as to hermetically seal the same.

The invention further aims to provide a 20 fastener, the locking bail of which is pivotally mounted on trunnions extended laterally from opposite sides of the jar and provided with depending offset ears which serve to receive the ends of the clamping bail, 25 thus dispensing with the usual ear-supporting wire around the neck of the jar and consequently reducing the cost of manufacture.

The invention further contemplates a two-part fastener, the clamping and locking bails 30 of which are stamped from sheet metal, the clamping bail having its intermediate and terminal portions rolled into substantially cylindrical form for engagement with the jar closure and offset ears of the locking bail, 35 respectively.

A still further object of the invention is generally to improve this class of devices so as to increase their utility, durability and efficiency.

40 Figure 1 is a perspective view of a fruit jar provided with a fastener embodying the present invention;

Fig. 2 is a side elevation thereof showing the locking bail in lowered or clamping position;

Fig. 3 is a perspective view of the locking bail detached.

Fig. 4 is a detail rear elevation looking at the opposite side of that jar from that 50 shown in Fig. 2.

Corresponding and like parts are referred to in the following description and indicated in all the views of the drawings by the same reference characters.

55 The improved fastener forming the subject-matter of the present invention is ap-

plicable to jars, bottles, cans and similar containers and by way of illustration is shown applied to a glass fruit jar in which 5 designates the body of the jar, 6 the neck 60 and 7 the lid or closure. Molded or otherwise formed integral with the neck of the jar are oppositely disposed trunnions 8, preferably arranged at one side of the vertical axis of the jar and having their fixed ends 65 provided with lateral enlargements 9 gradually merging into the neck of the jar and which serve to reinforce the trunnions, as shown.

The fastener comprises a locking bail 10, 70 preferably stamped or otherwise formed from a single strip of resilient metal bent into substantially semi-circular form and having its opposite ends enlarged to form upstanding ears 11 pierced by transverse 75 apertures 12 for the reception of the trunnions 8 and on which the locking bail is pivotally mounted for swinging movement. The metal constituting the locking bail 10 is offset laterally immediately below the ears 80 11, as indicated at 13, and thence extended downwardly to form depending ears 14 also provided with apertures 15, adapted to receive the terminals of a clamping bail, indicated at 16. The opposite edges of the 85 metal at the intermediate portion of the locking bail 10 are preferably bent or rolled laterally at 17 so as to reinforce and strengthen the bail and also to present a smooth rounded surface for contact with 90 the fingers of the operator when clamping the closure in position over the mouth of the jar.

The clamping bail 16 is also preferably 95 formed of a single strip of flat metal, the opposite longitudinal edges of said strip at the ends thereof being bent or rolled into substantially cylindrical shape, as indicated at 18, to form reinforced terminals, the ends of which are bent inwardly to form lugs 19 100 which latter pass through the apertures 15 of the ears 14 so as to permit lateral swinging movement of the clamping bail with respect to the jar and thus allow the lid or closure 7 thereof to be applied or removed 105 when desired. The opposite longitudinal edges of the clamping bail 16 at the center thereof are preferably bent or rolled together to form a cylindrical portion 20 adapted to fit between locking lugs 21 on the 110 upper surface of the closure 7. The clamping band 16 is also preferably reinforced

and strengthened by the provision of the longitudinal upstruck ribs 22 disposed one on each side of the cylindrical portion 20 of the bail and preferably conforming to the curvature of the lid or closure where the clamping bail contacts therewith.

The apertures 12 and 15 are so arranged that when the locking bail is in horizontal position said apertures will be in vertical alinement with each other and in vertical alinement with the trunnions 8. When the clamping bail 16 is moved to a position over the lid 7, however, and the locking bail depressed, the ears 14 will be tilted rearwardly and the apertures 15 moved to a position out of vertical alinement with the trunnions 8 thereby causing said ears to exert a downward clamping action on the bail 16 and force the lid 7 against the washer 23 and thus hermetically seal the mouth of the jar. It will be noted that the clamping band 16 is arranged at the center of the jar while the trunnions 8 are offset with respect thereto. Consequently, when the locking bail 17 is swung downwardly, the ears 14 will be moved to a position at the rear of the trunnions 8 and thus lock the bails 16 and 17 against further movement. In order to release the lid or closure 7 it is merely necessary to exert a slight upward pressure on the locking bail 17 which will swing the ears 14 forwardly and upwardly thereby releasing the clamping bail 16 so that said clamping bail may be swung to one side of the jar and thus permit removal of the lid or closure. The offset or shoulder 13 is preferably disposed in alinement with the lower longitudinal edge of the locking bail 17 and serves to space the ears 14 a sufficient distance from the neck of the jar to accommodate the pivots or lugs 19 and thereby prevent the lugs from contacting with the wall of the jar when operating the fastener.

By making the locking bail 10 of spring metal sufficient resiliency is provided to cause the ears 11 to frictionally engage the lugs 8 and thus prevent accidental separation of the parts.

While the fastener is principally designed for use on fruit jars, it will, of course, be understood that said fastener may be applied to bottles, cans and other containers without departing from the spirit of the invention. It will also be understood that the fasteners may be made in different sizes and shapes and nickled, japanned or otherwise coated or treated so as to give the same a neat attractive appearance.

Having thus described the invention, what is claimed as new is:

1. The combination with a container including a closure, of a locking bail formed of a flat sheet of metal pivotally mounted on the container and having its pivoted ends provided with depending ears offset with respect thereto, and a clamping bail pivotally connected with said ears and adapted to bear against the closure when the locking bail is swung downwardly, the opposite longitudinal edges of the locking bail at the center thereof being rolled laterally to form a finger piece.

2. The combination with a container including a closure, of trunnions extending laterally from the opposite sides of the container beneath said closure and disposed at one side of the vertical axis of the container, a locking bail having upstanding ears journaled on the trunnions and provided with laterally offset portions terminating in depending ears, and a clamping bail pivotally connected with the depending ears.

3. The combination with a container having laterally extending trunnions and provided with a closure, of a locking bail pivotally mounted on the trunnions and provided with depending perforated ears, and a flat clamping bail having its opposite ends rolled to form cylindrical portions, the terminals of which are bent inwardly and passed through the perforations in the depending ears to form a pivotal connection between the locking bail and said clamping bail.

4. The combination with a container having laterally extending trunnions and provided with a closure having spaced locking lugs on the upper surface thereof, of a locking bail pivotally mounted on the trunnions and provided with depending perforated ears offset with respect thereto, and a clamping bail formed of a flat sheet of metal having its opposite longitudinal edges at the ends thereof rolled into substantially cylindrical form and thence bent laterally to form lugs fitting within the perforations in the depending ears, the opposite longitudinal edges of the metal constituting the clamping bail being rolled laterally at the center thereof to form a cylindrical portion adapted to fit between the locking lugs on the closure, there being reinforcing ribs formed in the clamping bail on opposite sides of the cylindrical portion thereof.

In testimony whereof I affix my signature.

JOHN W. LIMBERT. [L.S.]
